UNITED STATES PATENT OFFICE.

WILLIAM F. HUNT, OF LINCOLN, NEBRASKA.

CALCULATOR.

No. 853,411.

Specification of Letters Patent.

Patented May 14, 1907.

Application filed December 13, 1906. Serial No. 347,707.

To all whom it may concern:

Be it known that I, WILLIAM F. HUNT, a citizen of the United States, residing at Lincoln, in the county of Lancaster and State of Nebraska, have invented certain new and useful Improvements in Calculators; and I do hereby declare the following to be a full, clear, and exact description of the invention, such as will enable others skilled in the art to 10 which it appertains to make and use the same.

My invention relates to certain new and useful improvements in calculators, and it has for its object the production of a device 15 whereby a number can be readily ascertained.

While I have shown in the accompanying drawings and shall describe herein the preferred form of embodiment of my invention, 20 it will be understood that changes may be made in the form, construction and combination of parts without departure from the nature thereof, as shown, described and claimed.

25 In the accompanying drawing illustrating my invention, Figure 1 is a plan or front view of the device. Fig. 2 is a rear view thereof. Fig. 3 a view of the device with the revolving dial removed. Fig. 4 a rear view of the 30 revolving dial. Fig. 5 is a central longitudinal section of my device.

Like numerals of reference denote similar parts in the several figures.

Upon a suitable support of any desired 35 form or size, I print preferably in vertical arrangement a series of columns of figures 2, six of such columns being illustrated in the drawings, but more may be employed if desired. The figures in these columns are so 40 arranged in the illustration shown that the device may be employed for ascertaining any number between one and sixty-three.

Below the double columns of figures 2, I place the letters 3, W. F. H. U. N. T, but as 45 will be obvious from the following description of the operation of my device, any other letters of the alphabet may be employed, or numerals or symbols may be employed instead of letters.

50 Below the letters 3, I provide a series of figures 4, as shown, arranged in circular form. Through the support or back piece 1, I provide a slot 5 on one side of which I place a series of tens units 6, running from a cipher (0) 55 to six (6), as shown in Fig. 2. At one side of the center of said back piece, I provide a hole

7 as shown in the same figure. On the back piece 1 and suitably journaled thereon by a stud 8, I provide a revolving dial 9, having near its edge a series of perforations 10 of 60 sufficient size to admit the point of a pencil or other device for the convenient rotation of the same. At one side of said dial, there is provided a recess 11 through which, as the dial is revolved, will be seen the series of 65 figures 4 on the back piece successively. On the back of the dial 9, as illustrated in Fig. 4 of the drawing, I arrange a series of figures 12, near the outer edge thereof; a series of figures 13 is so arranged on the back of the 70 dial 9 at different distances with reference to the axis of the dial, so that in the revolution thereof each of said figures will appear through said slot 5 and at its proper relation with one of the group of figures 6. As the 75 dial is rotated the series of figures 4 on the back piece will, as stated, successively appear through the orifice 11 in the dial, and on inverting the structure the series of figures 12 will successively appear through the hole 7 80 in such back piece, and one of the figures of the series of figures 13 will be seen through the slot 5 in the back piece. Suitable stops 14, 15 are provided in the back piece; these are preferably holes registering with the 85 holes 10 through the dial, so that a pencil point or other instrument employed for the rotation of the dial will drop into such slots when one of the holes 10 comes opposite thereto or registers therewith, thereby temporarily stopping the further rotation of the 90 dial.

It will be obvious that the structure may be made of card board, thin wood, or even of light metal, as may be found most desirable 95 in its manufacture, and the material employed forms no part of my invention, and I do not wish to be considered as being limited to the use of any particular material. It will be also understood from the operation of my 100 device that other and various forms or arrangement of the figures may be employed, and the necessary slots or orifices in the structure may be changed.

Having described the preferred embodiment of my invention, I will now point out the manner of its use, and how the same may be employed to ascertain what may be termed a "concealed number", or any number between 1 and 63. To ascertain any 110 number between those stated, it is first necessary to find such number in the six double

columns at the top of the device. Then have a fixed or predetermined point on the dial, which point may be an arrow 16 pointing to the stop 14; then place a pencil or 5 other point in the hole 10 opposite the first column in which the desired number is found, turn the dial with the point in the direction of the arrow at the letter under such column, until the point falls into and is stopped by 10 the hole or stop 14. This is done commencing from each column in which the desired number is found. When the successive rotations of the dial have been accomplished, the desired number can be ascertained in any 15 one of three ways; first, it is seen through the hole 11, in the face of the dial; second, through the hole 7 in the back of the support or back piece 1; third, through the slit 5 in the back of the support or back piece 1, on 20 the left side of which is printed the tens numeral, the unit numeral being seen through the slot. As an illustration, the person operating the device is told by another person that his age being 45 years, he states that the 25 same appears in the columns lettered F. H. N. T. The dial being now turned so that the arrow points to the stop 14, a pencil point is placed in the hole 10 of the dial opposite the letter F and the dial turned to the right, as 30 indicated by the arrow under said letter, until it stops at 14. The pencil point is then put in the hole 10 opposite the mark under the letter H and the dial is again turned to the right until it stops at 14. The pencil is 35 then placed in the hole 10 opposite the letter N, and the dial again turned to the right until stopped at 14. The pencil is then placed in the hole 10 opposite the letter T and turned to the left as indicated by the arrow, 40 until the pencil falls into and is stopped at 15, when the figure 45 will appear on the back piece 1 and can be read through such opening in the face of the dial. Then by inverting the device the figure 45 is seen through 45 the hole 7 on the back thereof and the figure 5 in the slot immediately at the side of the figure 4 printed on the back of the dial 9, thus making the number 45.

It will be understood that a fourth method 50 of disclosing the figure sought may be employed by the making of a slit in the face of the dial, and having the tens units on the edge thereof, the unit units opening on the face of the back piece and being seen through 55 such slit. It will also be understood that instead of employing the six columns of figures, as 2, names, designs, or pictures can be employed in lieu thereof; thus the six columns might be constituted of given names instead 60 of figures.

While my device is particularly adapted for amusement purposes, it is obvious that it can also be utilized as an advertising device by the printing of suitable advertising matter thereon. It can be manufactured at a 65 minimum of cost, which fact renders it of practical utility for either of said purposes.

Having thus described my invention what I claim as new and desire to secure by Letters Patent is

1. In a mechanical calculator the combination with a fixed supporting member having a series of columns of figures arranged thereon and designated by indicating characters, a series of figures arranged adjacent 75 said first named series, a perforation through said member, a slot therethrough and a series of tens numerals adjacent to said slot, of a movable member pivotally mounted on said first member, and provided with a slot 80 through which the series of figures over which it is rotatably mounted may be read, and provided on its back with a series of figures which successively appear as it is moved through the opening on the back of said 85 first named member, as set forth.

2. In a mechanical calculator, the combination with a fixed supporting member having a series of figures arranged upon its face and rear side, a movable member pivoted 90 thereon and having a series of figures on its side adjacent to the fixed member on which it is mounted, openings through the fixed member through which the numbers on the rear side of the movable member are exposed, and slots in the rotating member through which the figures on the front of the fixed member are exposed, as set forth.

3. In a mechanical calculator, the combination with a fixed member having a series 100 of figures thereon designated by indicating characters, a second series of figures arranged relatively adjacent to said indicating characters, a member movably mounted on said fixed member and having a series of perforations therein arranged to align with the figure column indicating characters on the fixed member, a plurality of figures on the rear of said movable member, and openings 105 in both of said members through which figures desired to be ascertained will appear according to the direction in which the movable member is moved and the extent of such movement.

In testimony whereof I affix my signature, 115 in presence of two witnesses.

WILLIAM F. HUNT.
